UNITED STATES PATENT OFFICE.

PAUL SCHÜTTLER AND STEPHAN LÖFFLER, OF CHARLOTTENBURG, NEAR BERLIN, GERMANY.

LIGHT-METAL PISTON, ESPECIALLY FOR USE IN CONNECTION WITH INTERNAL-COMBUSTION ENGINES.

Application filed January 26, 1925. Serial No. 4,713.

To all whom it may concern:

Be it known that we, PAUL SCHÜTTLER and STEPHAN LÖFFLER, citizens of the German Republic, and residents, respectively, of 55
5 Wilmersdorferstrasse, Charlottenburg, near Berlin, Germany, and of 6 Witzlebenplatz, Charlottenburg, near Berlin, Germany, have invented a new and useful Improved Light-Metal Piston, Especially for 60
10 Use in Connection with Internal-Combustion Engines (for which we have filed application in Germany July 18, 1923), of which the following is a specification.

Running internal combustion-engines 15 equipped with pistons of a light metal, such as aluminium, magnesium, or the like, or an alloy of any one thereof, is connected with difficulties in that it is by no means a simple matter to ensure the proper fitting-in play 20 with consideration to the various conditions of service of the engines, as well as to the heat-effects. One succeeds, for instance, to fit in pistons of the kind in question in such a manner that they run unobjectionably at 25 full load, but clapper and hammer at the starting of the engine, in cold state of this latter, so strongly, that an unobjectionable service is rendered questionable.

The object of our invention is to obviate 30 this drawback, and we attain that object by the improved piston illustrated by way of example in the accompanying drawing in which Figure 1 is a side-view of this piston, Figure 2 an axial section therethrough, Figure 3 a cross-section in the plane A—A of Fig. 2, Figure 4 a cross-section in the plane B—B of Fig. 4, and Figure 5 an end-view of the piston, showing its open end.

The piston consists, as regards its circumferential wall, of four parts which, although being made integrally, are distinguished from one another by their different heat-conductive capacity, in that there are two oppositely located parts *f f* having internal 45 projections *b b* intended to receive the piston-pin, and two oppositely located parts *g g*, as shown in Figs. 2-4.

The piston-wall parts *g g* are separated 50 from the closed top of the piston by transversely disposed slots *d d*, and from the piston-wall parts by rows of holes *e e e e*. The conduction of the heat from the closed piston-top to the wall-parts *g g* is, therefore, greatly impeded, whereas no imped-

ing means, as regards the conduction of heat, 55 is provided between the piston-top and the wall-parts *f f*. In the contrary, internal ribs, such as *i*, or similar ones, may be provided just to facilitate the conduction of the heat from the piston-top to the wall-parts 60 *f f*. But as regards impeding the conduction from the wall-parts *f f* to the wall-parts *g g*, there may be provided, besides the holes *e e e e*, longitudinal grooves or 65 channels *s s s s* located either (as in Figs. 3 and 4) internally or, if desired or preferred, externally (not shown). The ribs *i* extend from the top of the piston down to the internal projections *b b*, as shown in Fig. 2.

Although the piston shall be practically 70 cylindrical in transverse section, we prefer to make the diameter D (Fig. 3) just a little longer than the diameter D', the ratio or proportion being such that the diameter D is that in which the piston fits properly into 75 its cylinder in cold state or in only moderately heated state, whereas the other portions of the circumferential surface of the piston will glide properly along the corresponding portions of the inner cylinder-wall 80 only later on when the cylinder and the piston have attained the temperature arising at full load of the engine. When the engine is started, the piston glides on the outer surfaces of its wall-parts *g g*, when it will fit 85 only partly into the cylinder, whereas it will fit properly at its entire circumference as soon as the temperature has risen during the ensuing continuous running of the engine. 90

We claim:

1. A light-metal piston, especially for use in connection with internal combustion-engines and having firstly, rows of holes extending parallelly to the axis of the piston and separating the wall-portions connected with the piston-pin from the other wall-portions, and secondly, transverse slots separating the latter wall-portions from the closed end of the piston, substantially as 100 set forth.

2. A light-metal piston, especially for use in connection with internal combustion-engines, and having, firstly, rows of holes extending parallelly to the axis of the piston and separating the wall-portions connected with the piston-pin from the other wall-portions; secondly, transverse slots separat-

ing the latter wall-ports from the closed end of the piston; and thirdly, longitudinal grooves located between the first-mentioned wall-ports and the other wall-ports, substantially as set forth.

3. A light-metal piston, especially for use in connection with internal combustion-engines, and having firstly, rows of holes extending parallelly to the axis of the piston and separating the wall-ports connected with the piston-pin from the other wall-ports; secondly, transverse slots separating the latter wall-ports from the closed end of the piston; thirdly, longitudinal grooves located between the first-mentioned wall-ports and the other wall-portion; and fourthly, internal ribs extending from the closed piston-end to the first-mentioned wall-ports, substantially as set forth.

4. A light-metal piston, especially for use

in connection with internal combustion-engines, and having firstly, rows of holes extending parallelly to the axis of the piston and separating the wall-ports connected with the piston-pin from the other wall-ports; secondly, transverse slots separating the latter wall-ports from the closed end of the piston; thirdly, longitudinal grooves located between the first-mentioned wall-ports and the other wall-portion; and fourthly, internal ribs extending from the closed piston-end to the first-mentioned wall-ports, substantially as set forth.

In witness whereof we have hereunto set our hands.

PAUL SCHÜTTLER.
STEPHAN LÖFFLER.
